UNITED STATES PATENT OFFICE.

GABRIEL D. COINER, OF WAYNESBORO, VIRGINIA.

STIRRUP.

1,127,187.

Specification of Letters Patent. Patented Feb. 2, 1915.

Application filed September 27, 1913. Serial No. 792,168.

To all whom it may concern:

Be it known that I, GABRIEL D. COINER, a citizen of the United States, and a resident of Waynesboro, in the county of Augusta and State of Virginia, have invented 5 an Improvement in Stirrups, of which the following is a specification.

My present invention relates to stirrups and more particularly to a stirrup in which provision is made for a certain amount of 10 flexibility and springiness while riding, in order to reduce sudden shock, and the object of my invention is to provide such an arrangement in a novel and simple manner together with certain means by which the 15 play or flexibility of the parts is limited in order to prevent their excessive action when mounting.

In the accompanying drawing which 20 illustrates my invention, Figure 1 is a perspective view of my improved stirrup. Fig. 2 is a front elevation thereof, the upper portion being broken away and in section in order to show the inner connections, 25 and, Fig. 3 is a side elevation of the stirrup.

Referring now to these figures, my improved stirrup consists of a body, the lower cross bar A, side portions A' and upper shank A² of which are integrally formed. 30 In accordance with my invention the upper shank A² is somewhat greater in proportion to the other parts than is usually the case and is provided with a central vertical bore a and a substantially squared upper end 35 upon which is seated a guide bracket B which in practice receives the stirrup strap, this bracket being provided with an apertured lug b depending from its under side and adapted to project within the upper 40 end of the bore a. At the lower end of the bore a a plate C is secured to the lower end of the shank A², by means of suitable fastening members indicated at c', this plate being provided with an unstanding lug c 45 which projects within the lower end of the bore a and opposes the lug b in spaced relation.

Extending through the bore a is a coiled spring D the ends of which are extended 50 through transverse openings of the lugs b and c in order to permit of relative movement between the guide bracket B and the stirrup and to elastically connect these parts, such movement being limited however, by 55 means of a flexible non-elastic connection in the form of a chain E, the ends of which

are secured through apertures in the inner extremities of the lugs b and c.

The chain E as will be seen by reference to Fig. 2 extends within the coiled spring 60 and serves to limit the relative movement of the strap and the guide bracket particularly when mounting inasmuch as it would be impractical to utilize a spring connection which would enable elastic relative movement between the parts while riding and at 65 the same time be of sufficient strength to resist excessive movement when mounting.

By means of the particular features described I am enabled to affect the desired 70 result and to provide a stirrup the formation of which will be simple, and will entail little if any additional expense over the usual ones.

I claim:

1. A stirrup provided in its upper portion with a vertical bore, a plate secured to the stirrup and closing the lower end of the bore, a relatively movable strap receiving guide disposed on the upper portion of the 80 stirrup, and flexible elastic and non-elastic connections between the guide and the said plate and extending within the bore, all for the purpose described.

2. A stirrup provided in its upper portion with a vertical bore, a plate secured to the stirrup and closing the lower end of the bore, a relatively movable strap receiving guide disposed on the upper portion of the 85 stirrup, and a spring disposed within the bore and having connection at its lower end to the plate and at its upper end to the strap receiving guide, for the purpose described.

3. A stirrup having a vertical bore 90 through its upper portion or shank, a plate secured to the stirrup and closing the lower end of the bore, a strap receiving guide bracket disposed on the upper end of the shank, a spring extending through the bore 95 and connecting the said plate with the bracket whereby to permit relative elastic movement between the stirrup and the guide bracket, and a flexible non-elastic connection between the said plate and the said bracket and also extending through the bore 100 whereby to limit the elastic movement between these parts, for the purpose described.

4. A stirrup provided with a vertical bore 105 in its upper portion or shank, a plate closing the lower end of the bore and secured to the shank, a stirrup receiving guide bracket disposed on the upper end of the shank, a 110

coiled spring extending through the stirrup bore and connecting the said plate and the said bracket whereby to permit of relative elastic movement between the bracket and the stirrup, and a chain extending through the spring and also connecting the plate and bracket whereby to limit the elastic movement between these parts, all for the purpose described.

10 5. A stirrup provided in its upper portion with a vertical bore, a plate secured to the stirrup and closing the lower end of the bore, a relatively movable strap receiving

guide disposed on the upper portion of the stirrup, said plate and said strap receiving 15 guide being provided with lugs projecting therefrom and within the respective ends of the stirrup bore, and flexible elastic and non-elastic connections between the said lugs and disposed within the bore, all substantially as described. 20
